UNITED STATES PATENT OFFICE.

FRED MUSTER, OF BERWICK, PENNSYLVANIA.

ADJUSTABLE CLEANER FOR GUIDE EYES FOR TEXTILE MACHINERY.

Application filed April 29, 1925. Serial No. 26,703.

This invention relates to certain new and useful improvements in adjustable cleaners for guide eyes used in connection with textile machinery, the object being to provide 5 a guide eye with a pair of adjustably mounted cleaners so constructed that they can be adjusted in respect to the guide slot of the guide eye so as to remove any dirt, waste or foreign matter adhering to the thread or 10 yarn in its passage therethrough.

Another and further object of the invention is to provide the guide eye with cleaner plates which can be adjusted towards each other and interchanged so as to bring a new 15 cleaning edge into position so as to operate on the thread or yarn so that the life of the cleaner plates is greatly increased, as each plate is provided with four cleaning edges, any one of which can be moved into position 20 to operate on the thread in its passage through the guide slot of the guide eye.

Another and further object of the invention is to provide a guide eye formed of a porcelain body having transversely arranged 25 bores or openings through which are adapted to extend bolts or screws for securing the cleaner plates in adjusted position thereon, whereby the plates can be readily attached or detached.

Other and further objects and advantages 30 of the invention will be hereinafter set forth and the novel features thereof defined by the appended claims.

In the drawings,

35 Figure 1 is a side elevation of a guide eye showing the application of my improved construction of adjustable cleaners thereto;

Figure 2 is a top plan view;

Figure 3 is a section taken on line 3—3 40 of Figure 1; and

Figure 4 is a perspective view of one of the cleaners detached.

In the drawing 1 indicates a guide eye 45 preferably formed of porcelain and substantially wedge-shaped in cross section having a longitudinal slot 2 in its upper edge and a transverse guide slot 3 through which the thread is adapted to pass, the upper edges of the porcelain block forming the guide eye 50 being inclined towards the slot as clearly shown. The forward edge of the porcelain block forming the guide eye is provided with a flange 4 and extending transversely through the block to each side of the guide slot 3 is an obliquely arranged bore 55

through which extend machine screws 6, on the outer ends of which are adjustably mounted cleaner plates 7 and 8, these plates being constructed identical in shape and the description of one will be sufficient for both. 60

These plates are square in shape and have their corners cut off or rounded and are provided with openings 9 of a greater diameter than the diameter of the machine screws 6 so that these plates can be adjusted towards and away from each other so as to form a proper clearance between the plates according to the size of thread passing 65 through the guide eye.

Each of the machine screws 6 carry a lock 70 washer 10 and a nut 11 for locking the plates in their adjusted position in respect to one another. These plates are adapted to rest on the flange 4 when in use as clearly shown so as to hold the side or adjacent edges of the 75 plates parallel with one another.

When one of the cleaning edges of either 80 of the plates becomes worn, by loosening the nut and removing the plate, the same can be placed back in position on the machine screws so as to place a new edge in position to operate on the thread and as these plates have four sides, the life of the cleaning plates is greatly increased by constructing the same in this particular manner. 85

In use the thread, cord or yarn passing 90 through the guide eye is thoroughly cleaned by the cleaning plates so as to remove any foreign matter therefrom and these plates form a stop for the thread, cord or yarn in case of an exceedingly large knot so that the 95 large knot can be cut out and a new one formed.

This adjustable cleaner is especially adapted to be used for winder guide eyes, but, it 95 is, of course, understood that it can be used in connection with any other guide eyes and all places where cleaners are essential in textile machinery and in use the guide eye is mounted on the guide rail in any suitable 100 manner so as to guide the thread, cord or yarn.

While I have shown certain details of construction, I am aware that various changes 105 can be made without departing from the spirit of my invention.

By forming the porcelain body of the guide eye with openings, I am able to attach the adjustable cleaner plates to the porcelain body in such a manner that it can be read- 110

ily attached or detached which provides a guide eye in which the cleaner can be used in connection therewith when desired.

What I claim is:—

- 1. A guide eye for textile machinery having substantially square cleaner plates mounted on one face thereof, said plates being adjustable and changeable to present new cleaning edges for the thread passing therethrough.
- 2. A guide eye for textile machinery comprising a porcelain block having a transversely arranged guide groove and provided with a flange, a pair of substantially square plates mounted on said flange and adjustable in respect to each other and changeable to present new cleaning edges

and means for locking said plates in adjusted position.

- 3. A guide eye for textile machinery comprising a wedge-shaped block having a transverse guide groove and provided with a horizontally disposed flange, bolts extending transversely through said block substantially square plates having openings of a larger diameter than said bolts arranged against one face of said block on said flange and lock washers and nuts for locking said plates in adjusted position in respect to one another.

In testimony whereof I hereunto affix my signature.

FRED MUSTER.
